UNITED STATES PATENT OFFICE

2,185,557

ELEVATOR BUCKET

Leon W. Koser, Winnipeg, Manitoba, Canada

Application September 20, 1938, Serial No. 230,836

2 Claims. (Cl. 198—152)

This invention relates to improvements in elevator buckets, the principal object thereof being to provide a sheet metal bucket formed from a one-piece patterned blank, having the base, rear wall, front wall and end walls integral with no other necessary means of fastening than a flange overlapping the base and front wall as a support against outward thrust.

A further object of this invention is to provide 10 a device of the character herewithin described which can conveniently be grouped in one nested bundle of elevator buckets thereby facilitating the handling thereof, reducing warehouse and shipping space and permitting of low freight 15 classification charges.

A further object of this invention is to provide 20 a device of the character herewithin described which will eliminate the use of overlapping flanges at the rear of the bucket for the purpose of presenting a smooth surface against the belt 25 at the rear thereof.

A further object of this invention is to provide 30 a device of the character herewithin described which can conveniently be shaped over a form and more accurately pressed to the desired form than has hitherto been possible with buckets made up from separate pieces.

A further object of this invention is to provide 35 a device of the character herewithin described in which the upper edges of the end walls thereof incline outwardly and upwardly to lessen the spillage of grain thereover.

A further object of this invention is to provide 40 a device of the character herewithin described in which the overlapping flanges thereof, act as a pair of tracks for the purpose of raising the dipping edge of the bucket slightly when the associated belt sags and the bucket scrapes the bottom of the loading pit.

With the above more important objects in view 45 and such other minor objects as may appear as the specification proceeds, my invention consists essentially in the arrangement and construction of details all as hereinafter more particularly described, reference being had to the accompanying drawing, in which:

Figure 1 is a plan view of the shaped blank employed in the manufacture of my elevator bucket.

Figure 2 is a perspective illustration of a completed bucket.

Figure 3 is a side view of Figure 2.

Figure 4 is a front view of Figure 2.

In the drawing like characters of reference indicate corresponding parts in the different figures.

My invention comprises a vertical rear wall 1, provided with a pair of spaced apertures 2, for the purpose of attaching the completed bucket to an elevator belt. The side walls 3 constitute part of the blank illustrated in the accompanying Figure 1, so that in the manufacture of my bucket, the blank is angulated along the lines 4 and by reference again to the accompanying Figure 1, it will be noted that the lines 4 converge from the edge 5 which constitutes the upper edge of the rear wall 1.

It will also be noted that the upper edge 6 of each of the side walls 3 is aligned with the edge 5, from which it is obvious that when the blank is placed in a press, the edges 6 will incline outwardly and upwardly as most clearly illustrated in the accompanying Figure 3. In this way, the possibility of spillage of grain over the side walls of my bucket is lessened.

The portion 1 is formed into a curved base portion 8, the contour thereof being struck about two radii 9 and 10, thereby forming two arcs 11 and 12. The front wall portion 13 is continuous to the arc 12, this wall being flat and diverging outwardly and upwardly towards the upper edge 14 thereof.

By reference to the accompanying Figure 1, it will be noted that I provide a pair of flanges 15, which in the process of forming a completed bucket are angled inwardly as clearly illustrated 30 in the accompanying Figures 2 and 4 to overlap the base 8 and the front wall 13. From which arrangement, it will now be apparent that the edges 16 and the turned edges 17 provide the only joints in my construction. It will also be 35 apparent that my inturned flanges 15 provide a peculiarly satisfactory support against the outward thrust of grain within the bucket upon the front wall 13.

It should finally be mentioned that the overlapping flanges 15 are spot welded at intervals 40 to the edges 12 or rivets may be employed for this purpose according as the bucket is large or small, after which the bucket is ready for bundling and shipping.

Since various modifications can be made in the above invention, and many apparently widely different embodiments of same, made within the scope of the claims without departing from the spirit and scope thereof, it is intended that all 50 matter contained in the accompanying specification shall be interpreted as illustrative only and not in a limiting sense and I desire only such limitations placed thereon as are specifically expressed in the accompanying claims.

What I claim as my invention is:

1. An elevator bucket formed from a one-piece patterned blank, said bucket comprising a rear wall, a pair of side walls continuous and integral therewith, a base and a front wall, said side walls converging inwardly towards said base, said base being integral and continuous with said rear wall and curving outwardly and upwardly, the curvature thereof conforming to two arcs, the first arc being struck from a radius of greater length than the height of said rear wall, the second arc being struck from a radius equal to approximately one-half the height of said

rear wall, said front wall being continuous and integral with the upper limit of said second arc and an integral flange extending along one edge of each of said side walls, said flange being angulated inwardly and overlapping said base and said front wall to prevent deformity thereof under the weight of material within said bucket.

2. The bucket as defined in claim 1 in which each of said flanges extend right up to the edge of said front wall to protect said edge against 10 mutilation.

LEON W. KOSER.
